UNITED STATES PATENT OFFICE.

WALTER GRAY SPAIN, OF DANVILLE, VIRGINIA, ASSIGNOR TO KAUMAGRAPH COMPANY, OF NEW YORK, N. Y., A CORPORATION OF NEW YORK.

TEXTILE-MARKING MACHINE.

Application filed July 2, 1925. Serial No. 40,994.

My invention relates to a new and improved machine for impressing transfers upon articles of wearing apparel such as stockings and the like.

5 One of the objects of my invention is to devise a machine whereby a paper strip having a series of transfers thereon can be automatically and intermittently fed in proper position in relation to a heated pressing head.

10 Another object of my invention is to simultaneously actuate the said strip of paper and the said pressing head so as to impress the trademark, design or the like to be transferred, upon the article.

15 Another object of my invention is to provide a machine whereby the paper feeding mechanism is actuated up and down simultaneously with the said pressing head.

20 Other objects of my invention will be further stated in the following description and drawings, it being understood that the general statement of the objects of my invention above specified is merely for the general explanation thereof and not to limit my invention in any particular.

Fig. 1 is a side elevation partially in section.

25 Fig. 2 is a section on the line 2—2 of Fig. 1.

Fig. 3 is a plan view.

Fig. 4 is an enlarged elevation showing the vertically movable parts in their highest position.

30 Fig. 5 is a view similar to Fig. 4 and showing the vertically movable parts in their lowest position.

Fig. 6 is a section on the line 6—6 of Fig. 4.

35 Fig. 7 is a section on the line 7—7 of Fig. 6.

Fig. 8 is a detail view of the gripping mechanism.

40 The machine is mounted upon a stand 2, connected by rivets 3 to base 1. A table 5 is connected to stand 2. Arms 30 provide bearings for a spindle 29 carrying a roll 28 of transfer paper P, which is fed through the parts mounted on vertically movable slide 27. The slide 27 is connected to two vertically movable rods 8, provided with guide collars 13 slidable within hollow guide tubes 9, closed by lower caps 10. The upper end of each guide tube 9 is held within a cap 11 secured to table 5 by suitable

bolts. The caps 11 have openings 18 and the tubes 9 have holes 17 so as to permit a flow of air into and out of tubes 9 at a predetermined rate when the tightly fitting collars 13 of rods 8 are moved up and down. 60 The rods 8 have pins 16 which fit into suitable grooves in the guide tubes 9, to prevent the rods 8 and collars 13 from turning. Compression springs 12 bear against the collars 13 and urge the rods upwardly to the 65 position shown in Fig. 1. The tightly fitting collars 13 act as pistons to produce the effect of a dash-pot, in combination with the openings 17 and 18, to check the movement of rods 8, and to prevent any jarring of the 70 parts. The lower caps 10 are mounted on a bracket 6 connected to stand 2. Each rod 8 passes through bracket 6. The bottom of each rod 8 is threaded and carries two adjustable collars 19, which limit the upward 75 movement of said rod.

A cable 22 is connected at 26 to the slide or support 27, passes through a guide 101 connected to the guide tubes 9, then passes around a pulley 20 pivoted at 21 to the bracket 6, and is then connected at 24 to the foot lever 23, pivoted at 25 to the column 2. A downward movement of foot lever 23 thus forces the support 27 downwardly, and the springs 12 operate to force the support 27 to its upper position. Each rod 8 passes through an enlargement 7 of the table 5. 85

The upper support 27 has longitudinal rails 42 and 43 rigidly connected thereto. A paper guide comprising channel members 30 is rigidly connected to said rails and the paper P is led through said guide and is fed forwardly in said guide by feeding mechanism which will be more fully described. As shown in Figs. 4 and 5, a lateral plate 52 is connected to rail 43 and this plate is provided with a resilient stamped-out tongue 58, whose position is regulated by screw 59, so that tongue 58 is forced against web P intermediate channels 30 with a regulated pressure. A roller 53 mounted on plate 55 is also forced against the paper P by a tension spring 56, connected to a projection 57 of plate 55. The plate 55 is provided with two arms pivotally 90 connected to plate 52. 100

An L-shaped arm 41 is connected to rail 42 and it carries a roller 40, which is connected to the take-up roller 39 by belt 38. 110 The take-up roller 39 has a spindle 33 which

is mounted on arms 44 and 45. These arms 44 and 45 are connected to uprights 46 and 47 which are connected to the support 27.

The paper is fed by means of a lower 5 movable feed plate 85 and an upper pivoted grip plate 86. The lower feed plate 85 has rail extensions 84, which slide on the rails 42 and 43. The feed plate 85 is also provided with a cable extension 97 through 10 which the cable 98 passes. The cable 98 is prevented from moving relatively with respect to projection 97 by any suitable means so that the cable 98 and projection 97 move together. The cable 98 has its right-hand 15 end provided with a weight 101 and its left-hand end is secured to stand or column 2 by pin 102. When the upper support 27 is lowered, the weight 101 is then free to pull the horizontal branch of cable 98 to the right and to also urge the plates 85 and 86 to the right. The upper grip plate 86 is pivoted at 87 to upright 83, which is connected to the lower plate 85.

The rear of the device is provided with 25 another upright 71 to which an angle lever 79 is pivotally connected at 78. The second upright 71 is also connected to plate 85. The upright 71 has a tension spring 81 connected to a branch 80 of lever 79, and the extension 30 77 of said lever carries a roller 76 adapted to turn upper plate 86 downwardly, to grip the paper P between the plates 86 and 85. At the right-hand side thereof, the plate 86 is provided with an L-shaped bar 89, which 35 is arranged in a lateral plane. A laterally disposed plate control lever 91 is pivoted at 92 to a short upright 93 connected to plate 86 adjacent the rear right-hand corner thereof. The front of said plate control lever 40 91 projects through the vertical slot of bar 89 and it is provided with a tongue 94 whose bottom is inclined towards table 5, and also extends to the right of said slot. A compression spring 96 which bears against plate 86, 45 forces said tongue 94 towards the top of the slot. The position of lever 91 is controlled by the screw 90. At the rear of the machine, a longitudinal lever 103 is pivoted at 104 to a short bar 105 connected to rear channel 50 member 30. A compression spring 106 forces the right-hand end 95 of lever 103 upwardly, so that it tends to urge the rear end or tongue 95 of lever 91 upwardly and thus tends to raise upper plate 86, when the 55 parts are in the position shown in Fig. 5.

A fixed cam 49 is connected to uprights 46 and 48, which are connected to support 27.

Hence, when the parts are in the position 60 shown in Fig. 4, the roller 76 is pressed downwardly, thus forcing plate 86 downwardly, so that the paper is gripped between the plates 85 and 86. When the support 27 is lowered, the plates 85 and 86 are moved to the right by cable 98 and pull the paper 65 P with them. The lower end of plate 86

may have rubber members 88 so that a firm grip on the paper can be secured. When the plates 85 and 86 are moved to the right, the tongue 92 passes along the underside of cam 49, and it is moved downwardly by the action of cam 49, so that the spring 96 is compressed, thus forcing the plate 86 more firmly against plate 85. Before the tongue 94 is released from cam 49, the lever 79 contacts with bar 50, which is connected to upright 47. This causes the roller 76 to be raised from plate 86. However, the lever 91 and spring 96 press the plate 86 downwardly until the tongue 94 is released from the cam. The lever 103 then operates to upwardly turn the plate 86, because said lever 103 contacts with the rear end of lever 91 and forces it upwardly. This releases the paper from the grip of plates 85 and 86. On the return stroke, the tongue 94 rides 75 on the upper surface of cam 49, so that it remains in the upper inoperative position even when lever 79 is spaced from bar 50. When the foot-lever 23 is released, the support 27 is free to rise, which produces the 80 return stroke of the feeding mechanism, while it is inoperative.

In order to operate the belt 38, the uprights 83 and 71 are connected by a horizontal extension 71' of said uprights 71. This horizontal extension is provided at the front of the machine with a lower fixed jaw 71'. An upper jaw 72 is pivoted at 73, and a compression spring 75 urges the upper movable jaw into the clamping position. A detent 67 is pivoted at 68 to extension 71' and it has a projection or hook adapted to engage the upper jaw 72 at the rear thereof, to prevent said upper jaw 72 from moving to the gripping position. The detent 67 is tripped by trip 65, pivoted at 64 to a bar 63, connected to lateral bar 61, which is connected to upright 41. A compression spring 66 urges trip 65 to the position shown in Fig. 5. When the plates 85 and 86 are moved to the right, the trip 65 turns detent 67 in the counter-clockwise direction, thus releasing the rear of movable jaw 72, which is moved upwardly by compression spring 75, thus causing the front of jaw 72 to grip the cable 38. Hence, during the feeding stroke, the support 27 is moved downwardly, together with the heated pressing head 32, which is connected thereto by member 34, and the take-up reel is simultaneously operated, thus keeping the paper P taut, and enabling the heated head 32 to mark the article placed beneath it.

At the end of the feeding stroke, the rear end of the movable jaw 72 contacts with the fixed cam 51, connected to upright 47, so that the jaw is released, because the rear end is depressed. When the rear end of jaw 72 has been thus depressed, the detent 67 is again forced to the holding position by 125

spring 70. Hence, upon the return stroke, the cable 38 is disengaged, and the detent 67 engages the end of trip 65 while it is in the position shown in Fig. 5 and moves it 5 to the position shown in Fig. 4.

In order to firmly grip the paper on the return stroke of the feeding mechanism, a clamp lever 117 is provided, which moves in the slot of a guide 118. The lever 117 10 is pivoted at 120. The clamp lever 117 is provided with an extension 119, which has a hole at the front thereof. A lever 112 pivoted at 113 to bar 114 enters said hole and is provided with a compression spring 115, which normally actuates lever 112 to move clamp lever 117 to the clamping position. The left-hand end of lever 112 is provided with a downwardly curved portion 116, which is adapted to be engaged by detent 20 108 pivoted at 109 and connected to tension spring 110.

At the end of the feeding stroke, the trip member 107, which is connected to movable upright 83, revolves detent 108 against the 25 force of tension spring 110, so that the lever 112 is released and the clamping lever 117 is caused to move to the clamping position. At the end of the return stroke of the feeding mechanism, the projection member 126, 30 which is connected to the bottom of plate 85, contacts with sleeve 127 of the slidable rod 125. This rod 125 is connected at 124 to lifter 121, which is pivoted at 122 to 114, so that the lifter 121 raises the left-hand end of lever 112 and thus moves the clamping lever to the inoperative position. When the lever 112 is turned to the position shown in Fig. 4, it is again engaged by 35 detent 108.

40 The pressing head 32 is provided with an extension 35 into which any suitable electrical heating element 36 can be inserted so as to heat the pressing head 32. The cable 37 carries the mains or leads for providing 45 current for the said electrical heating element. The sides of the stand 2 are removable and they are held in place by means of bolts 4.

50 The operation of my device is as follows:—

An article or a pile of articles such as stockings or the like are placed upon the table 5 so that the top of the article or of the pile of articles is sufficiently high to 55 enable the head 32 to exert the required pressure before the support 27 contacts with table 5. Each article is placed in such position with respect to the pressing head 32 that the desired transfer will be made at the 60 proper point. The operator then leads the transfer paper P through the members 30 and through the other parts of the machine and he winds up the front of the strip, which is preferably blank, upon the take-up 65 roller.

The operator then presses upon the foot lever 23. The support 27 is at such a distance above the table 5, that the impression on the strip P which is to be transferred is moved beneath the pressing head 32 before 70 the said pressing head 32 presses the said impression against the article on the table 5, or against the top of the pile of articles placed upon the table 5.

It is obvious that the desired forward 75 feed of the strip P takes place when the member 27 has been lowered for a certain definite distance and that any further downward movement of the member 27, after this predetermined preliminary movement, 80 does not affect the position of the strip P in any manner. Hence, the apparatus can be used for impressing the desired impressions upon each of a pile of articles placed 85 in proper position upon the table 5.

It is only upon the return or upward movement of the member 27 that the reverse movement of the feeding mechanism takes place and this reverse movement does not take place until the head 32 no longer 90 presses the strip P against the article supported upon the table 5.

It is also obvious that when the member 27 is in its upper position that the belt 38 can be manipulated so as to adjust the position of the paper P. This enables the operator to secure proper registration of the next transfer impression upon the strip P after the feeding mechanism has slipped or if such proper registration has not been secured for any reason whatever. 95

I have shown a preferred embodiment of my invention, but it is clear that numerous changes and omissions could be made without departing from its spirit. 100

Thus, while I have shown the support 27 as being mounted directly above the table 5, and movable towards and away from said table 5 in a vertical direction, it would be 105 obviously an equivalent if the said support 27 were movable in any other direction than the vertical.

I claim:

1. A marking machine comprising a table adapted to support the object to be marked, 115 a movable pressing head movable towards and away from the said table, a support movably mounted with respect to the said table and adapted to be moved towards said table and away therefrom, guide means 120 located on the said support and adapted to guide a strip of paper underneath the said pressing head, movable feeding mechanism movable to and fro and mounted upon the said support and adapted to feed the said 125 strip of paper towards the said pressing head, control means mounted upon the said support and adapted to cause the said gripping means to grip the said strip of paper upon the feeding stroke thereof and to re- 130

lease the said gripping means from the said strip of paper upon the return stroke of the said feeding means, and a cable connected to the said feeding means, the said cable being mounted to a fixed support at one end thereof and having a weight connected to the free end thereof whereby the said cable is actuated by said weight to move said feeding means and to cause them to feed the strip forwardly when the said support is moved towards the said table, and said cable also operates to return the said feeding means to their original position when the said support is moved away from the said table.

2. In a marking machine, the combination of a table adapted to support the object to be marked, a support movably mounted with respect to the said table and movable towards and away from said table, a lower plate movably mounted upon the said support, an upper plate also movably mounted on the said support, the said plates being adapted to grip and feed a strip of paper, a control mechanism adapted to force said plates together so as to grip the said strip of paper, actuating means operable when said support is moved towards said table to actuate the said plates in a feeding stroke, the said control mechanism being operable during said feeding stroke to cause said plates to grip the said strip of paper, and release mechanism mounted upon the said support and adapted to cause the release of the grip of the said plates upon the said paper upon the termination of the feeding stroke.

3. A device according to claim 2, which also has additional clamping means adapted to grip the said strip of paper after the said feeding stroke has been completed and means adapted to release the said additional clamping mechanism during the said feeding stroke.

4. In a marking machine the combination of a table adapted to hold the object to be marked, a support movably mounted with respect to the said table and movable towards and away from the said table, a lower plate movably mounted upon the said support, an upper pivoted plate connected to the said lower plate and movable therewith, spring means movable with said plates and adapted to force the said pivoted plate against the said lower plate, means adapted to move the said plates to and fro when the said support is moved towards said table and away from the said table, and control means adapted to release the said upper plate from the said lower plate when the said plates are being moved in the direction corresponding to the movement of the said support away from the said table.

5. In a marking machine the combination of a table adapted to hold the object to be

marked, a support movably mounted with respect to said table and movable towards and away from said table, a lower plate slidably mounted upon the said support, means adapted to move the said lower plate to and fro when the said movable support is moved towards and away from the said table, an upper pivoted plate connected to the said lower plate and movable therewith, a spring-actuated lever connected to said lower plate and adapted to force the said upper plate against the said lower plate, a transverse lever pivotally connected to the said upper plate and having a tongue projecting beyond the said plate, a compression spring intermediate the said lever and the said plate, a cam mounted upon the said support and stationary with respect thereto and adapted to engage the said tongue and downwardly force the same during the feeding stroke of the said plates, control means adapted to force the said spring-actuated lever away from the said plate before the end of the said feeding stroke and supplemental means adapted to force the said tongue to the upper side of the said cam at the completion of the feeding stroke, so that the said tongue rides upon the upper surface of the said cam and the said upper plate is held spaced from the said lower plate upon the return stroke of the said plates.

6. In a marking machine, the combination of a table adapted to hold the object to be marked, a support movably mounted with respect to said table and movable towards and away therefrom, a movable head movable towards and away from said table, feeding and guiding means mounted on said support and adapted to feed and guide a strip of transfer paper or the like under said head, a clamp lever mounted on said support and adapted to clamp said strip, a spring connected to said lever and adapted to urge it to the clamping position, a detent mounted on said support and adapted to hold said clamping lever in the inoperative position, a spring connected to said detent and adapted to cause it to engage said clamping lever, means mounted on said support and operative at the completion of the forward feeding stroke of said feeding mechanism to trip said detent and release said clamping lever, and means mounted on said support and operable at the end of the backward return stroke of said feeding mechanism and adapted to actuate said clamping lever to the inoperative position, so that it is again held in said position by said detent.

7. In a marking machine, the combination of a table adapted to hold the object to be marked, a support movably mounted with respect to said table and movable towards and away therefrom, a movable

head movable towards and away from said table, feeding and guiding mechanism mounted on said support and adapted to feed and guide a strip of transfer paper or the like under said head, a take-up roller for said strip mounted on said support, and operating means for said take-up roller mounted on said support and adapted to 10 actuate said take-up roller during the feeding stroke of said feeding mechanism.

8. In a marking machine, the combination of a table adapted to hold the object to be marked, a support movably mounted with respect to said table and movable 15 towards and away therefrom, a movable head movable towards and away from said table, feeding and guiding mechanism movably mounted on said support and adapted to feed and guide a strip of transfer paper or the like under said head, a take-up roller 20 for said strip mounted on the said support, a second roller mounted on the said support, a belt connecting the said rollers, and gripping mechanism connected to the said 25 feeding mechanism and adapted to grip and actuate the said belt when the said feeding mechanism is moved in one direction, and release mechanism for the said gripping mechanism adapted to release the grip there- 30 of at the end of the said stroke.

9. In a marking machine, the subcombination of a table 5, a support 27 movably mounted above said table 5 and movable towards and away from the said table 5, a 35 lower plate 85 slidably mounted upon the support 27, an upper plate 86 connected to the said lower plate 85 and movable with respect thereto, and a cable 98 connected at one end to a fixed connection 102 and having a weight 101 connected to the free end thereof, the said cable 98 having a horizontal branch mounted on rollers 99, the said horizontal branch being connected to the lower plate 85.

45. 10. A marking machine according to claim 9 in which the upper plate 86 is pivotally mounted and is forced downwardly by a pivoted lever 79 connected to the said upper plate and having a tension spring 81, the said upper plate 86 also having a transverse lever 91 pivotally mounted thereon and provided with a compression spring 96, the said transverse lever 91 having a 50 projecting tongue 94 adapted to be engaged by the underside of a fixed cam 49 after the feeding stroke has commenced and up to the completion of the feeding stroke, and a fixed rod 50 adapted to engage the first-mentioned pivoted lever 79 and to release 55 the pressure thereof from the upper plate 86 before the completion of the feeding stroke, so that the grip between said upper plate and said lower plate is released.

60. 11. In a marking machine, the subcombination of a table 5, a support 27 movably

mounted with respect to said table 5 and movable towards and away from said table 5, a lower feeding plate 85 slidably mounted on the support 27, an upper pivoted gripping plate 86 pivotally connected to said lower plate 85, a cable 98 connected at one end to a fixed support 102 and having a weight 101 connected to the other end thereof, the said cable 98 having a horizontal branch connected to the said lower plate 85, 70 a transverse lever 91 pivotally mounted upon the upper plate 86, a compression spring 96 intermediate the said lever 91 and the said gripping plate 86, the said lever 91 having a tongue 94 projecting beyond one edge of the gripping plate 86, said lever 91 having another and rear tongue 95 projecting beyond the other edge of the said gripping plate 86, a fixed cam 49 having a substantially straight lower edge and also having 80 an upper edge provided with arcuate ends, the said lower edge of the fixed cam 49 being adapted to engage and downwardly force the said first-mentioned tongue 94, and means mounted upon the said support 27 adapted to engage and upwardly throw the said rear tongue 95, after the said first-mentioned tongue 94 has been forced along the underside of said cam 49 and is free 85 from engagement therewith. 90

12. In a marking machine, the subcombination of a table 5, a support 27 movably mounted with respect to said table 5 and movable towards and away therefrom, a lower feed plate 85 slidably mounted on the support 27, an upper gripping plate 86, a first upright 83 connected to the said lower feed plate 85, the said upper gripping plate 86 being pivoted to the said upright 83, a second upright 71 connected to the said feed plate 85, the said second upright 71 having a horizontal extension 71' provided with a jaw member 71², an upper jaw 72 pivotally connected to the said extension 71', a compression spring 75 adapted to force 110 the end of said upper jaw 72 towards the jaw member 71², a take-up roller 39 connected to the support 27 and adapted to take up a strip of marking paper or the like which is fed by the movements of the said plates 85 and 86, a second roller 40 connected to said support 27, a cable 38 connected to the said take-up roller and said second rollers and adapted to actuate them, the said cable 38 passing between the said jaw member 71² and the adjacent portion of the said upper jaw 72, a spring actuated detent 67 adapted to hold the upper jaw 72 in the inoperative position and a spring actuated pivoted trip 65 having an inclined end adjacent the said detent 67, the said trip 65 being adapted to trip the said detent 67 during the feeding stroke of the said plates 85 and 86, so as to permit the upper jaw 72 to move towards the jaw 120 125 130

member 71² to grip the said cable, and a cam member 51 connected to the support 27 and adapted to force the said upper jaw 72 to the inoperative position at the end of the feeding stroke, to be again engaged by the detent 67, the said detent 67 being pivotally connected to the second upright 71.

13. In a marking machine, the subcombination of a table 5, a support 27 movably mounted with respect to said table 5 and movable towards and away from said table 5, a lower feeding plate 85 slidably mounted upon the support 27 and having an upright 83 connected thereto, an upper gripping plate 86 pivoted to the said upright 83 and adapted to grip a strip of marking paper or the like located intermediate the said plates 85 and 86, a guide 118 through which the said strip of marking paper is adapted to be led, a clamp lever 117 adjacent said guide 118 and adapted to clamp the said strip of paper in the said guide 118, a lever 112 adapted to urge the said clamp lever 117 to the operative position, a compression spring 115 adapted to operate the said lever 112 so as to cause the said clamp lever 117 to be moved to the clamping position, a detent 108 pivotally connected to the said support 27 and having a tension spring 110 adapted to actuate the said detent 108 so as to hold the lever 112 in the position in which the clamp lever 117 is inoperative, a trip member 107 connected to the said lower plate 85 and adapted to actuate the

said detent 108 at the end of the feeding stroke so that it is caused to release the lever 112, a lifter 121 adapted to move the said lever 112 against the force of the compression spring 115 into a position in which the clamp lever 117 is inoperative, and means actuated upon the return stroke of the said plate 85 to operate the said lifter and to permit the said detent 108 to again engage the said lever 112.

14. A marking machine having a table 45 adapted to support the object to be marked, a support movably mounted with respect to said table and having channel guides adapted to guide a strip of paper and to cause said strip of paper to move in unison with said movable support, a pressing head fixed to said support and movable in unison therewith, a take-up roller for said strip of paper mounted on said support and movable in unison therewith, movable feeding means mounted on said support and adapted to grip and feed a strip of paper in said channel guides, operating means for said gripping and feeding means adapted to be actuated when said support is moved relative to said table.

In testimony whereof I hereunto affix my signature.

WALTER GRAY SPAIN.
